UNITED STATES PATENT OFFICE.

JACOB SULEDER, OF BROOKLYN, NEW YORK, ASSIGNOR TO THE KEUFFEL & ESSER COMPANY, OF HOBOKEN, NEW JERSEY, A CORPORATION OF NEW JERSEY.

CALCULATING-MACHINE.

975,654.

Specification of Letters Patent. Patented Nov. 15, 1910.

Application filed April 2, 1910. Serial No. 553,102.

To all whom it may concern:

Be it known that I, JACOB SULEDER, a citizen of the United States, and resident of Brooklyn, in the county of Kings and State of New York, have invented certain new and useful Improvements in Calculating-Machines, of which the following is a specification.

This invention relates to calculating machines and its novelty consists in the construction and adaptation of the parts as will be more fully hereinafter pointed out.

There has long been upon the market a class of calculating machines adapted for use in performing the operations of addition, subtraction, multiplication and division, a machine of such class forming the subject matter of United States Letters Patent to Alexander Rechnitzer, No. 809,075, dated January 2, 1906 and another forming the subject matter of French patent to Thomas No. 138,912, dated September 29, 1880, in which the upper casing of the machine is provided with a series of slots alongside of which are displayed numerals in denominational series and in which slots buttons are adapted to slide and which buttons are connected by appropriate means with the calculating mechanism so that when the buttons are adjusted opposite the proper numerals the items so set up are used in performing the operations of arithmetic above indicated. The machine is also supplied with a series of numeral wheels upon the peripheries of which numbers are displayed in such a manner that as the wheels are rotated in the performance of the calculations mentioned, these numbers appear in turn beneath a series of eight apertures in a tiltable section of the upper casing of the machine, the series of numbers in sight in such apertures constituting at any time the result of the numerical calculation undertaken. Commonly this machine is used in performing single operations of addition, subtraction, multiplication or division and the numeral wheels referred to registering

the result are returned to zero by means of a canceling bar manually operated slideable in suitable bearings in the side of the machine and actuated from a handle projecting through its upper casing, and it is customary for the operator after performing a numerical calculation, for instance, that of multiplication, and after reading the result from the figures in sight in the line of apertures above referred to, to restore all of the numeral wheels to zero by pushing the handle connected to the canceling bar to the left. Now it sometimes happens that successive operations are desired to be performed with the machine and the results of such successive operations are required to be added together. In such case it is obvious that it is not desirable to make use of the canceling bar to restore the numeral wheels to zero until the entire series of operations is concluded, but such is the effect of muscular mechanical memory that the operator unconsciously and inadvertently frequently moves the canceling bar in the midst of such a series of operations, when he does not intend to do so, and thus loses the result which he is seeking to obtain and is compelled to perform the operations over again.

The purpose of this invention is to provide means by which this accidental, or inadvertent movement, of the canceling bar handle is prevented and it comprises a manually operated locking member which can be moved by the operator into the path of the canceling bar handle before a series of operations, the results of which are to be accumulated, are commenced, and he is thus prevented from accidentally destroying the results of the calculations upon which he is engaged.

In the drawings, Figure 1 is a top plan view of a machine embodying the invention, Fig. 2 is a transverse section and partial side elevation on an enlarged scale of a portion of the mechanism on the plane of the line 2-2 in Fig. 3, Fig. 3 is a rear elevation of the left end of the tiltable plate, Fig. 4

is a top plan view of the left end of such plate showing the safety lock engaged with the canceling bar handle, Fig. 5 is a perspective of the safety lock and Fig. 6 is a perspective detail of the canceling bar handle and its connections.

In the drawings, 10 is the upper fixed plate of the calculating machine, and 20 is the upper tiltable plate of the same.

10 11, 11 are slots in the plate 10, and along side of which are displayed the numerals in series.

15 13, 13 are buttons sliding in said slots and designed for use in enumerating one series 15 of items used in the calculations.

14, 14 are eight openings in the plate 10 through which numbers 15, 15 displayed on numeral wheels beneath the openings may be seen.

20 16 is the actuating handle for the series of such numeral wheels.

25 17 is the handle of a restoring bar, the purpose and function of which is explained in Letters Patent of the United States issued July 7th, 1908 to Tobias Bauerle.

21, 21 are eight openings in the plate 20 and through them can be seen numbers 22, 22 displayed on numeral wheels 23 arranged beneath such openings.

30 24, 24 are also eight openings in this same plate 20 and 25, 25 are numerals displayed on such numeral wheels 23 and visible through the eight openings 24.

35 30 is the handle of a restoring or canceling bar 31 which is provided with notches 32 adapted to engage cam teeth 33 secured to the rear side of each wheel.

40 Without describing this mechanism in detail, it is sufficient for the purposes of this description to say that when the bar 31 is moved toward the left by the handle 30 the notches 32 engage these cams 33 and move the wheels all in the same direction and until each one of them is so positioned that 45 the zero displayed on it is seen through one of the eight openings 24. The canceling bar is automatically retracted to its original position by means of a spring 34.

45 None of the parts so far described comprise the invention herein claimed.

50 The handle 30 moves in a slot 40 in the plate 20. Arranged at a convenient place on the plate 20 is a screw 41 having a slit head 42. Beneath the head and in sliding 55 contact with the plate 20 is a locking plate 43 having an upturned flange 44 serving as a handle or finger piece, and a slot 45 to engage the screw 41. It also has a recess 46 to engage and hold the handle 30.

60 When the locking plate 43 is in the position shown in Figs. 1 and 2 and the screw 41 is turned down to hold the plate against the plate 20, it is obvious that the canceling bar handle 30 is in no way interfered

with, while if the screw 41 is loosened sufficiently to allow the plate 43 to be slid forward into the position shown in dotted outline in Fig. 1, it is evident that the canceling bar handle can not be moved to the left beyond the edge 47 of the plate 43 and, as this movement is not sufficient to allow the canceling bar 31 to restore the numeral wheels to zero, it is also evident that when so positioned, the plate 43 will prevent any accidental cancellation of the number accumulated on these numeral wheels while it will not otherwise interfere with the operation of the machine. When the calculation is finished and it is desired to return the wheels to zero, the plate 43 is moved to its former position by the flange 44.

65 It may at times be desirable to prevent any actuation of the numeral wheel series; for instance, while the machine is being moved. In such case the plate 43 is moved forward and the canceling bar handle 30 is held until it can engage with the recess as shown in Fig. 4, and thereafter the canceling bar handle and the bar itself can not be moved until the plate 43 is moved.

70 75 80 85 90 95 100 105 110 115 120 125 90 95 100 105 110 115 120 125

What I claim is:—

1. In a machine of the character described, an upper plate provided with eight apertures, numeral wheels in series arranged beneath the same, a bar adapted to simultaneously move all the wheels to register zero through the eight openings, means comprising a handle for manually moving the bar, and means for locking the handle to hold all the wheels at zero, the same means serving to prevent the handle being moved from a zero setting position.

2. In a machine of the character described, the combination with a canceling bar and its handle of a manually movable plate adapted to be interposed to prevent its movement to a certain position and which plate is provided with means to lock the handle at such position if it is moved thereto.

3. In a machine of the character described, the combination with a canceling bar and its handle of a manually movable plate adapted to be interposed to prevent its movement to a certain position comprising a sliding plate having a finger piece and set screw.

4. In a machine of the character described, the combination with a canceling bar and its handle of a manually movable plate adapted to be interposed to prevent its movement to a certain position and which plate is provided with means to lock the handle at such position if it is moved thereto comprising a plate provided with a recess.

5. In a machine of the character described, the combination with a canceling

bar and its handle of a manually movable plate adapted to be interposed to prevent its movement to a certain position and which plate is provided with means to lock the handle at such position if it is moved thereto comprising a plate provided with a recess, the edge of the plate contacting with the handle to limit its movement and

the recess embracing the handle to hold it in position.

Witness my hand this 21st day of March, 1910, at New York, N. Y.

JACOB SULEDER.
